(57) **CLAIM**

The ornamental design for a hexlock wrench, as shown and described.

DESCRIPTION

The present invention is an ornamental design for a wrench, of which the following is a specification, reference being made to the accompanying drawings, forming a part hereof. FIG. 1 is a perspective view of a hexlock wrench, showing the preferred embodiment of the present new design.

FIG. 2 is a top view of the hexlock wrench of FIG. 1.

FIG. 3 is a front view of the hexlock wrench of FIG. 1.

FIG. 4 is a first perspective view of the hexlock wrench of FIG. 1.

FIG. 5 is a second perspective view of the hexlock wrench of FIG. 1.

FIG. 6 is a third perspective view of the hexlock wrench of FIG. 1.

FIG. 7 is a first side view of the hexlock wrench of FIG. 1.

FIG. 8 is a second side view of the hexlock wrench of FIG. 1.

FIG. 9 is a third side view of the hexlock wrench of FIG. 1; and,

FIG. 10 is an exploded side view of the thumb wheel portion of the hexlock wrench of FIG. 1.
